UNITED STATES PATENT OFFICE.

JAMES DENNIS ROOTS, OF WEST KENSINGTON, LONDON, ENGLAND.

SYSTEM OF AERIAL RAILWAYS.

Application filed January 29, 1920. Serial No. 354,976.

To all whom it may concern:

Be it known that I, JAMES DENNIS Roots, a subject of the King of Great Britain, residing at 58 Avonmore Road, West Kensington, London, W. 14, England, have invented a System of Aerial Railways, of which the following is the specification.

The object of this invention is to provide a new system or method of and means for 10 an aerial railway especially for crossing arms of the sea, straits, or channels that it is impossible to bridge, or impossible or non-paying to tunnel, and that may be used where desirable over land areas where great speeds 15 may be obtained for carrying relatively light loads. Where carried over the sea it may be carried at such a height as to be considerably above the highest masts so as to preclude the possibility of any interference 20 with navigation.

I provide a plurality of towers or masts which may conveniently be of steel and may be of the lattice or trellis type of construction or similar thereto, and a steel cable is 25 stretched from the tops of the two towers or over more of such towers according to the length of rail required.

The steel cable is not intended to carry a load, or only a relatively small amount, 30 under normal conditions at any time.

I so construct or adapt an airship as to run along the said rail. The airship is provided with two or more deeply grooved or double flanged wheels secured upon axles or 35 fixed shafts preferably with roller bearings. The said grooves in the wheels fit over and engage the said cable.

The wheels are arranged in pairs one such pair of wheels is fitted beneath the airship or 40 aeroplane and under the forward end at each side, and the other set under the rear end of the aircraft on each side.

Two such ropeways or cables may be arranged preferably horizontally and parallel 45 or side by side with relation to each other.

I may prefer to provide a rudder or rudders at the forward end of the airship or aeroplane as well as at the rear in order that by co-operation of the rudders and elevators 50 at each end, the thrust of the propellers co-acting with the rudders, may relieve the cable or cables as far as possible of all lateral wind stresses.

The cables are anchored to earth in the 55 rear of a long hangar, which forms the ter-

minus station so that when by the air brakes the machine slackens speed it may be protected from the force of the wind.

The ropeways thus arranged in parallel pairs of rope tracks are in order to make 60 them as nearly straight as possible and with the minimum of catenary dip or sag in the middle between the tower or trestle or mast supports, or each pair of same, provided with a carrier or supporting rope for each rail 65 rope, which carrier rope is given the most suitable degree or extent of sag and intermediate supporting ropes of smaller gauge or diameter are provided connecting the carrier and rail ropes together after the manner 70 of a suspension bridge support. The said sag will be determined by the distance between the successive supporting towers or trestles.

I am aware that it has been proposed before to support a single rail rope by a carrier 75 rope with intermediate suspension ropes in order to bring to a minimum the catenary sag of the rail rope.

On the pair of parallel ropes or rails for the aircraft between which and under restraint of which the aircraft flies, that is to say, the aircraft under normal conditions of running, relieves the two rope rails of load by weight and the steering effect relieves it 80 of load by wind stresses due to pressure of 85 wind on the aircraft. The ropes therefore under normal conditions serve as guide tracks, there being normally always a tendency of the aircraft to lift the ropeway at the point of contact of the wheels with the 90 ropes.

I construct an airship with a transverse spar or member in the fore part of same carrying preferably two grooved wheels one pair at each end of the span or diameter to 95 engage the ropeways, and a second similar spar or member at the rear end of the craft having a similar pair of grooved wheels at each end of same. I may provide means for carrying the said eight grooved wheels upon 100 the airship by extensions of the present framework of same, upon which extensions the said wheels are mounted. In an aeroplane the wheels are likewise secured to extensions of the main spars as afterward 105 shown.

By the described construction long spans between the trestle or tower supports may be constructed of say one mile in length with for example a rope of special steel of two 110

inches diameter and a dip or sag of say two hundred and twenty feet.

In carrying such a ropeway across the sea or straits the towers are built on large caissons, sunk in suitable positions and filled with cement, earth and the like.

Means may be provided to limit or prevent independent wind swing of each pair of ropes by cross or transverse rope connections of the carrier ropes or of suspension ropes. Or the transverse connection may take the form of a steel tube of greater diameter in the centre tapering to the ends.

The rail rope is preferably connected to the suspension ropes by means of two steel plates for supporting the former. The plates are provided with a half round groove at their edges adapted to grip the rope when clamped together by bolts, each plate being

tapered also to an edge at outside of the groove and also at the ends in order to provide at entrance and leaving of the wheels as gradual an ascent as possible for the upper wheels, and a similar gradual descent

for the lower wheels in passing over the plates. The main plate has a right angled or curved bend to permit of the passage of the wheels and the suspension rope is suitably secured at the top of the plate. One or

both of the wheels may be carried on springs secured to the aircraft in order that while the spring or springs may tend to be pressed together to hold the wheels on the rope, allowance may be made for the in-

creased thickness or diameter of the supporting plates relatively to the rail rope, and to permit the distance between the wheel centres to be increased, as well as to provide smoother running.

The aircraft is preferably provided with such a number of internal combustion engines, each with a propeller, that two out of six for example, may fail, without causing the failure of the aircraft.

I may provide means for automatically operating the front and rear rudders and elevators upon the aircraft when the lateral or vertical stresses upon the ropeway, the former due to wind, have reached a predetermined amount, by for example the heeling of the airship upon the ropeway. The high speed of the airship thus co-operating with the action of the rudders will automatically relieve the ropeway of all excessive stresses, especially during gusts of wind. The said rudders and elevators will also have means for control at will of the usual kind.

The main novel features of this system are:—

1. The aircraft is run from fixed point to point under restraint of rails or ropeways to ensure safety in reaching destination at all times, and to eliminate that element of great risk at all times existing but especially during fog while retaining only partly reduced

by wheel friction the advantage of high speed.

2. The aerial ropeway or railway carries no load except under abnormal conditions, the load being carried by the aircraft, and indeed the aircraft should give a lifting effect to the rail or rope over which it passes, with the consequence that there is no additional sag on the ropeway at that part at the moment guiding or carrying the aircraft and the friction upon the wheels and their bearings is thus a minimum.

3. The lateral wind stresses which would otherwise come upon the ropeway due to the wind pressure upon the aircraft especially so an airship are met as far as possible by turning the rudder to a suitable angle and in some cases employing fore and aft rudders for this purpose.

4. That the aircraft is kept at a high rate of speed from station to station in order to fulfill the condition expressed in paragraph 3 and screens are provided at the stations to take wind stresses on reducing speed and wind brakes consisting of hinged planes with vertical surfaces to open may be employed to arrest the motion of the aircraft at the station as quickly as possible, which as stated is provided with lateral screens with or without a roof, the ropeway passing through the station thus formed.

Reference should be made to the accompanying sheets of drawings which illustrate the preferred manner of carrying the invention into effect.

Fig. 1 is a view in elevation of the novel system showing an airship running upon a pair of ropeways.

Fig. 2 is an end view of the arrangement shown in Fig. 1.

Fig. 3 is an end view of the half section of an airship with the means of support of the rail rope on the inner side of the lattice tower.

Fig. 4 is a half section of an airship with the means of support of the rail rope from the carrier rope.

Fig. 5, Sheet 2, is a sectional view of a portion of an airship frame showing an arrangement of rail rope carrier rope and suspension rope.

Fig. 6 is an elevation of a portion of the rail and carrier and suspension ropes as shown in Fig. 5.

Fig. 7 is an end view of the wheels and the securing means of the rail rope to the lattice tower.

Fig. 8, Sheet 3, is a plan view of an aeroplane as mounted upon aerial ropeways.

Fig. 9 is an end view of an aeroplane so mounted.

Fig. 10 is a detail view of the two wheels and one wing of the aeroplane.

Fig. 11 is an end view of a pair of wheels and springs of same.

Fig. 12 is a view of the tail plane of same with its wheels on the rail rope.

A A are the trellis towers or other suitable supports for the carrier and rope rail-
ways of the system, example shown in Figs.
1 and 2. In order to arrange the trellis
towers or supports as widely apart as possi-
ble and yet to enable the rail rope to be as
far as possible a straight line and without
sag thereon, each of the two rail ropes B is
supported on the two respective carrier ropes
C which are secured upon the tops of the
towers or trellis supports A, or upon trans-
verse girders A¹ upon the supports or towers
A, each rail rope B is supported by its car-
rier rope C by means of suspension ropes
D. The suspension ropes D are secured to
the carrier ropes C, C, at suitable intervals
apart, and the two carrier ropes C, are ar-
ranged with the necessary degree, or the
minimum suitable degree of sag or catenary
dip for the distance apart of the trellis tow-
ers or supports A. The lower end of each
suspension rope D has clamped or bolted
thereon steel supports or carrying means E,
these are shown to a larger scale in Fig. 5.
The carrier E consists of a steel curved arm
E¹ having means at the upper end for
clamping or securing the suspension rope D.
The clamping means consist of a plate E² formed
integrally with the support arm E having
a groove or recess therein to receive
the rope D and the plate E² is bolted to the
plate E¹ and clamps the suspension rope D
between the two plates.

The lower end of the steel carrier E is
widened into a relatively thin steel plate E³ and
at its outer edge a half round groove E⁴ is
formed to receive the rope B. A sep-
arate steel plate F is provided arranged to
be bolted as shown to the plate E³ and
formed also at its outer edge with a half
round groove to correspond with the first
mentioned half round groove. When the
plate F is bolted to the plate E³ the rail
rope B is clamped or secured within the two
said half round grooves so formed and is
thus securely held between the two said
plates. The rope carrier E is extended in
this manner into a thin plate to clamp the
rope with its corresponding clamping plate
so that at the engaging position of the
grooved wheels G, G¹, there shall be the
minimum resistance or obstacle provided
against the passage of the said wheels over
the carrier, from the rail rope B and on
to the rope again, and for this purpose the
carriers E are arranged on the two rail and
carrier ropes not exactly opposite each other
but slightly staggered so that the wheels on
the one side of the aircraft as afterward de-
scribed shall enter upon and leave the car-
rier plates E⁴ and F before the correspond-
ing wheels on the other side engage with the
thin carrier plates clamping the rope B.

The two carrier ropes C are secured in
parallel relation on the top of the supports
or towers A or the trellis girder connecting
them A¹ and the two rail ropes B are also
parallel with each other throughout, each
rail rope being immediately beneath its sup-
porting carrier rope supported at inter-
vals therefrom by the vertical suspension
ropes D.

Figs. 3 and 4 indicate diagrammatically
two half sections of an airship S, the one
half section S¹, Fig. 3, being shown when
the airship is passing on the rail rope B
one of the pillars or trellis towers A showing
a bracket H secured to the left hand
side pillar of the trellis support A. The
bracket at this point carries the rail rope
B and a bracket is shown to a larger scale
in Fig. 7. The other half section Fig. 4 is
shown when the airship is at an intermedia-
te or approximately midway position be-
tween the supports A as shown in Fig. 1.

The carriers E secured to the suspension
ropes D are shown to a larger scale in Figs.
5 and 6.

Stiffening or strengthening spars I are
provided within the airship S to carry the
laminated springs J, to the ends of which
springs the short or stub axles K are rig-
idly bolted, upon which axles the grooved
wheels G, G¹, are mounted. Portions of the
framing S² of the ship are shown in Figs.
3, 4, 5 and 7.

The two wheels G, G¹, are on opposite
sides of, one above and the other below, the
rail rope B, and as shown in Figs. 1, 2, 3
and 4, one such pair of wheels engage both
steel ropes B B on the fore part of the air-
ship S, one pair on each side of the airship
and two pairs of corresponding wheels simi-
larly engage each rope B at the rear part
of the airship and on both sides of same, so
that there are four pairs of such grooved
wheels. Operating normally there will al-
ways be a lift action in the lighter than air
vessel S as also in the aeroplane P, and con-
sequently only the four wheels G¹ engaging
the two ropes beneath same need be in actual
pressure contact. The upper four flanged
or grooved wheels G serve to assist in re-
taining the airship on the rail ropes while
running normally and would only come into
frictional or pressure engagement with the
two ropes in the event of the airship losing
buoyancy to a sufficient degree or in the case
of an aeroplane to lessen speed.

There being eight wheels secured to the
airship by the springs J, four above and
four below the pair of rail ropes B, the
grooves in the wheels thus engaging the
ropes on both sides vertically provide ad-
ditional security against the airship leav-
ing the ropes in a high wind, and to meet
and relieve lateral wind pressure upon the
airship the rudder is set at an angle in such

a manner as if the airship were free it would turn its head into the wind, thereby relieving the rail ropes of lateral stresses.

Figs. 8, 9, 10, 11 and 12, Sheet 3, show the employment of a heavier than air machine, an aeroplane, to the system of aerial railways similarly arranged as described with rail ropes B carrier ropes C and suspension ropes D with reference to the foregoing figures. The aeroplane P has its four main wing spars M of each wing L stiffened in order to carry the laminated springs J which are bolted or secured to the ends of each of the spars M. On the outer ends of the springs J are bolted the stub axles K upon which are mounted the grooved wheels G, G¹. The grooved wheels G are secured to the front spars of each wing, and the wheels G¹ to the rear spars of each wing. The grooved wheels G as shown engage the rail ropes B, B, on each side of the aeroplane on the top of the rail rope and the four flanged or grooved wheels G¹ on the under side of same.

The aeroplane P shown is of the twin engined type. The tail plane O is preferably of extended span and may be of the lifting type. It is provided with front and rear main spars N in a similar manner to those of the wings, and on the end of each spar N are fitted similar laminated springs J and stub axle K carrying smaller and lighter grooved wheels G, G¹, as shown in Fig. 12, engaging respectively above and below the rail rope B as before described.

In a similar manner to that before described with respect to the airship S the rudder Q may by being placed at a suitable angle relieve the parallel ropes B of lateral wind stresses while the aeroplane is travelling at a high speed.

In Fig. 11 the springs are shown secured to the ends of the main wing spars M instead of as in Fig. 9 in order that the springs may not render less efficient a portion of the ends or tips of the main wings.

What I do claim as my invention and desire to secure by Letters Patent is:—

1. In an aerial railway system, a ropeway the ropes of which are supported in parallel relation and an air-craft capable of flying above the rails when free and provided with grooved wheels engaging the upper and lower surfaces of the ropes of the two ropes of the ropeway, the wheels being arranged at the sides of the aircraft, and guiding and maintaining it midway between the two ropeways.

2. In an aerial railway system for guiding aircraft in flight, two rail ropes arranged in parallel relation, two catenarian and parallel carrier ropes or cables supported above the rail ropes, suspension or supporting ropes connecting the rail and carrier ropes at intervals, and an aircraft capable of free flight and guided between the two ropeways spaced apart with the aircraft between the ropeways.

3. In an aerial railway system for guiding aircraft in flight, spaced supports, four ropes supported by the supports, two of the ropes being catenarian carrier ropes parallel with each and the other two being rail ropes below the carrier ropes, vertical suspension ropes connecting the rail and carrier ropes, and an air ship capable of free flight and guided by the two ropeways which are spaced apart with the airship between the ropeways.

4. In an aerial railway system, parallel rail ropes, an airship mounted to travel on the rail ropes and between the said ropes, and a rudder mounted on the air ship and arranged at an angle to the rail ropes, whereby the rail ropes will be relieved of lateral wind stresses.

5. In an aerial railway system for guiding aircraft in flight, a ropeway having rail ropes, carrier ropes, suspension ropes secured to the carrier ropes, and metallic curved arms having their upper ends secured to the suspension ropes and provided at their lower ends with means for holding and supporting the rail ropes.

6. In an aerial railway system, a ropeway, an aeroplane having strengthening wing spars, and a grooved wheel mounted on the outer end of each wing spar and adapted to engage the rope of the ropeway.

7. In an aerial railway system for guiding aircraft in flight, supports, a ropeway, brackets secured to the supports, each bracket comprising two metallic plates having half round grooves and secured together and clamping a rope of the ropeway, and an air craft traveling on the ropeway.

8. In an aerial railway system, parallel rail ropes, an aeroplane, and two pairs of grooved wheels mounted on each side of the aeroplane at the outer ends of the wings, the wheels engaging the upper and lower surfaces of the rail ropes, both being arranged in the vertical plane of the rail ropes, one above and the other below the said rail ropes.

JAMES DENNIS ROOTS.
